UNITED STATES PATENT OFFICE

105,416

DESIGN FOR A BOTTLE

Jacob S. Sherman, Chicago, Ill.

Application May 24, 1937, Serial No. 69,526

Term of patent 7 years

To all whom it may concern:

Be it known that I, Jacob S. Sherman, a citizen of the United States and resident of Chicago, in the county of Cook and State of Illinois, have invented a new, original, and ornamental Design for a Bottle, of which the following is a specification, reference being had to the accompanying drawing, forming a part thereof.

Fig. 1 is an elevational view of a bottle showing my new design;

Fig. 2 is a top plan view of the same;

Fig. 3 is a cross sectional view through the same, said sectional view being of only one-half of the bottle, the other half being symmetrical with the part shown.

I claim:

The ornamental design for a bottle, substantially as shown.

JACOB S. SHERMAN.
